CLAIM

The ornamental design for an interlabial absorbent device, as shown and described.

DESCRIPTION

FIG. 1 is a perspective view of an interlabial absorbent device embodying my design;

FIG. 2 is a top plan view thereof;
FIG. 3 is a right side view thereof, the left side view being
a mirror image in appearance;
FIG. 4 is a bottom plan view thereof;

FIG. 5 is a front view thereof; and,
FIG. 6 is a back view thereof.
